UNITED STATES PATENT OFFICE

ANDREW P. ANDERSON, OF BROOKLYN, NEW YORK, ASSIGNOR TO THE LAMSON COMPANY, OF SYRACUSE, NEW YORK, A CORPORATION OF MASSACHUSETTS

CONVEYER

Application filed January 3, 1931. Serial No. 506,396.

This invention relates to an improvement in conveyers and more particularly in conveyers of the type in which loads are raised or lowered by supporting means which travel upwardly or downwardly in a vertical well.

It has heretofore been the practice in conveyers of this type to load the supporting means from one side only of the well and the primary object of this invention is to provide a conveyer wherein the carrying surfaces of the load supporting means are divided so that loads can be supplied thereto from opposite sides of the well, these operations being performed independently and the efficiency of the conveyer being thereby doubled or at least appreciably increased.

A further object of this invention is to provide in a conveyer comprising a plurality of load supporting flights traveling in the well, a partition in the well transversely of the flights and intermediate the ends thereof which partition divides the carrying surfaces of the flights so that the surfaces of the flights at one side of the partition are supplied with loads independently of the surfaces at the other side.

Other objects of this invention will appear from a consideration of the following description and of the accompanying drawings wherein:

Figs. 1 and 2 are side and end elevations respectively of a conveyer embodying this invention; and

Fig. 3 is an enlarged cross-sectional view thereof.

I have elected to show a conveyer of the type illustrated in the Gibbs Patent No. 1,504,886 modified to embody my invention, but it will be understood that I am not limited thereto and that other types of conveyer may be similarly modified. That elevator comprises a shaft-way divided into walls 10 and 11 to which access at the different floors of a building is given by openings 12 and 13 through the frame thereof. Traveling in the wells are a plurality of flights 15 supported on pairs of chains or belts 16 and 17. The pairs of chains 16 travel over head and foot pulleys 18 and 19 respectively while the pairs of chains 17 travel over head pulleys 20 and

21 and foot pulleys 22 and 23. Suitable means, such as an electric motor 24, drive the head pulleys 18 and 20 through a chain 25 from a pulley 26. The various pulleys and the motor are suitably supported upon the frame defining the shaft-way.

Intermediate the ends of the flights 15 is supported in each well a partition 30 suitably anchored at its upper end to the elevator frame. As shown particularly in Fig. 3 the flights 15 travel freely past the side edges of the partitions 30, such flights being provided in the present embodiment with notches 31 substantially midway of their length into which the edges of the partition project.

Mounted upon the partition are angle bars 32 which act to stiffen the partitions and also as shown in Fig. 3 to determine the location of the trays, one of which, designated as A, is shown in position. The partition 30 thus divides the load supporting surfaces of the flights, those on one side of the partition being accessible from the openings 12 while those on the other side are accessible from the openings 13.

As will be well understood, the flights 15 are caused to travel through the wells at the same rate of speed so that the inner and outer flights coact in pairs to support the trays A. The trays are introduced onto the flights through the openings 12 and 13 in the well casing and may be loaded independently from either side of the wells. The trays loaded onto the flights in the well 10, in which the flights travel upwardly, are re-

moved when they arrive at the proper station. The trays loaded onto the flights 15 in the well 10 may be automatically removed by a conveyer belt 35, as shown in Figs. 1 and 2.

It will be understood that the term "well" has been herein employed to designate the space in which the conveyer travels to transport articles and is not limited in the architectural sense to a part of the construction of the building itself.

While one form of embodiment of this invention has been shown and described, other forms thereof and other embodiments may obviously be made without departing from

the spirit and scope of the invention as set forth in the following claims.

I claim:

1. A conveyer adapted to transport articles in a well having openings in the opposite sides thereof and comprising a plurality of load supporting flights, means for causing the flights to travel in the well, and means for dividing transversely the load supporting surfaces of the flights, whereby loads may be supplied thereto independently through the openings at opposite sides of the well.
2. A conveyer adapted to transport articles in a well having openings in the opposite sides thereof and comprising a plurality of load supporting flights, means for causing the flights to travel in the well and a transverse partition in the well, past the ends of which the flights travel freely, for dividing the load supporting surfaces of the flights, whereby loads may be supplied thereto independently through the openings at opposite sides of the well.
3. A conveyer adapted to transport articles in a well having openings in the opposite sides thereof and comprising a plurality of load supporting flights notched intermediate the ends, means for causing the flights to travel in the well, and a partition in the well extending transversely of the flights, the side edges of said partition entering the notches in the flights, whereby the flights travel freely along the partition and loads may be supplied independently to the flights through the openings at opposite sides of the well.
4. A conveyer adapted to transport articles in a well having openings in the opposite sides thereof and comprising a plurality of load supporting flights notched intermediate the ends, means for causing the flights to travel in the well, and a partition in the well secured at its upper end and extending transversely of the flights, the side edges of said partition entering the notches in the flights, whereby the flights travel freely along the partition and loads may be supplied independently to the flights through the openings at opposite sides of the well.

Signed by me at New York city New York
this 17th day of December, 1930.

ANDREW P. ANDERSON.
